UNITED STATES PATENT OFFICE

168,700

PERSPIRATION SHIELD FOR EYEGLASSES

Herbert E. Nichols, Los Angeles, Calif.

Application April 15, 1952, Serial No. 19,329

Term of patent 7 years

(Cl. D57—1)

To all whom it may concern:

Be it known that I, Herbert E. Nichols, a citizen of the United States of America, residing in the city of Los Angeles, in the county of Los Angeles, States of California, have invented a new, original, and ornamental Design for a Perspiration Shield for Eyeglasses, of which the following is a specification, reference being had to the accompanying drawing, forming a part thereof.

Fig. 1 is a front perspective view of a perspiration shield for eyeglasses showing my new design; the fragmentary showing of supporting eyeglasses in broken lines being for illustrative purposes only;

Fig. 2 is a front elevational view thereof;

Fig. 3 is a side elevational view; and

Fig. 4 is a top plan view.

The broken lines are omitted from Figs. 2-4 for convenience of illustration.

I claim:

The ornamental design for a perspiration shield for eyeglasses, substantially as shown and described.

HERBERT E. NICHOLS.
